UNITED STATES PATENT OFFICE.

HARVEY C. HAYES, OF WASHINGTON, DISTRICT OF COLUMBIA.

SUBMARINE SOUND TRANSMITTER.

Application filed January 9, 1924. Serial No. 685,291.

My invention relates to submarine sound transmitters and more particularly to those termed oscillators, and has for an object the prevention of sound energy radiated into water from an oscillator returning and being absorbed by the skin of a vessel by providing a solid inertia backing in the region of the oscillator.

A further object is to increase signal strength without causing distortion or elongation of signal due to reverberation.

With the above and other objects in view the invention consists in the construction, combination and arrangement of parts as will be hereinafter more fully described.

The usual manner of installing oscillators is to cut a hole through the vessel's skin such that the oscillator diaphragm can project through the plating with its outer surface in contact with the surrounding medium and flush with the outside of the hull, being secured in position by riveting to the vessel's skin a flange carried by the oscillator.

It has been found, however, that with this installation a considerable part of the sound energy radiated traverses a short curved path and returns to the vessel's hull. This is due to the fact there is not sufficient inertia back of the plane of the oscillator to prevent the high compression waves from displacing the ship's hull toward a region of pressure release within the hull. To remedy this defect it has become customary to back up the vessel's skin or plating surrounding the oscillator with a tank filled with liquid, this procedure having increased the strength of the signals considerably, but this gain has been offset by reverberation set up in the tank causing distortion and elongation of the signals instead of permitting a desired rapid succession of short, clear cut signals.

By backing up the vessel's skin with a solid inertia, such as lead or cement, all of the benefits of an inertia backing are obtained without the ill effects resulting from tank backings. Much less sound energy builds up and resonates within the comparatively small volume of the solid inertia, as its coefficient of reflection for those sound waves that meet the surface from the water outside the hull is greater than in the case of a tank, and the sound is, therefore, reflected and does not enter the inertia material.

The method of mounting an oscillator having a solid inertia backing may be best understood from the following description and the accompanying drawing forming part of this specification. The figure shows a cross-section of a vessel's hull having an oscillator mounted thereon. As the oscillator forms no part of the present invention, it is not illustrated in detail. Also, it will be understood that while but one side of a vessel is shown equipped with an oscillator and its backing, both sides may be so provided, and if necessary a number may be mounted on each side.

In the drawing 5 indicates the skin of a vessel to which is secured an oscillator 6 by a flange 7. The region of the vessel's skin adjacent to the oscillator is backed by an inertia material 8, preferably lead or cement. The inertia backing may be placed inside or outside the vessel, but if outside the diaphragm is preferably so placed that it will be flush with the outer surface of the backing.

It will be understood that the above description and accompanying drawing comprehend only the general and preferred embodiment of my invention and that various changes in form, proportion and minor details of construction may be resorted to without departing from the principle or sacrificing any of the advantages of this invention as claimed.

Having described my invention, I claim:

1. In combination, a source of sound located in the hull of a vessel and attached thereto and solid annular means surrounding the source of sound having inertia coefficients greater than that of the hull and that of the surrounding water.

2. In combination, a source of sound located in the hull of a vessel and attached thereto, an annular plate of solid material having a greater coefficient of inertia than the section of the hull covered thereby.

3. In combination, a source of sound located in the hull of a vessel and attached thereto, an annular plate of solid material having a greater coefficient of inertia than that of the section of the hull covered thereby and that of the surrounding water.

4. In combination, a source of sound located in the hull of a vessel and attached thereto, a plate of lead surrounding the

source of sound, said plate having sufficient weight to dampen the vibrations produced within the hull surrounding the source of sound.

5. In combination, a source of sound located in the hull of a vessel and attached thereto, a plate of lead surrounding the

source of sound and rigidly attached to the hull of the vessel, said plate having sufficient weight to dampen the vibrations produced within the hull surrounding the source of sound. ¹⁰
